O. GÜNTHER

FEED WATER HEATER

Filed Feb. 9, 1923

OTTO GÜNTHER, INVENTOR.

BY O. V. Thiele

HIS ATTORNEY.

UNITED STATES PATENT OFFICE.

OTTO GÜNTHER, OF ESSLINGEN, GERMANY, ASSIGNOR TO THE SUPERHEATER COMPANY, OF NEW YORK, N. Y., A CORPORATION OF DELAWARE.

FEED-WATER HEATER.

Application filed February 9, 1923. Serial No. 618,026.

To all whom it may concern:

Be it known that I, OTTO GÜNTHER, residing at Esslingen, Wurttemberg, Germany, a citizen of Germany, have invented certain new and useful Improvements Relating to Feed-Water Heaters, of which the following is a specification.

Feedwater heaters, such as those for locomotives which are exposed to all sorts of weather, are often damaged by frost, largely owing to the fact that the usual inlet and outlet cocks favour such freezing, and that the means now in use for draining off the water and allowing the air to escape from the horizontally arranged feedwater tubes are very inadequate, the low head of water being insufficient to overcome the resistance to flow in the horizontal tubes. The known arrangements for draining under pressure of steam or air are too complicated and require too much attention from the attendants.

The object of my invention is to remove these disadvantages.

The invention is illustrated in the accompanying drawing, showing one embodiment thereof.

As shown in the drawings, in order to prevent the freezing of the cocks, the cock and head for the feed water heater are made as an unitary structure so that the cock is heated by conduction from the head, this preferably being accomplished by casting the cock integral with the head.

Fig. 1 is an end view of a head for a feed water heater, the cover of the heater being omitted and the cock shown in longitudinal central section, Fig. 2 is a section on the line 2—2 of Fig. 1 and Fig. 3 is a detail section through the valve also taken on the line 2—2 of Fig. 1 but showing the valve plug in draining position. The feed water heater 10 is provided with a tube sheet 11 in which the ends of the water tubes 12 are secured; the tube sheet 11 being held in place by the head A and a lagging cover 14 being provided to encase the entire heater.

In the form shown in the drawing, the casing 1 of the combined draining and filling cock is formed integral with the head A and is provided with the branches 1^a, 1^b and 1^c cored out to provide the outlet passage 6, the inlet passage 3 and the draining passage 7^a respectively. A drain pipe 7 is connected with the branch 1^c and the branches 1^a and 1^b are flanged to provide means for

connecting the usual inlet and outlet pipes thereto.

The central part of the casing 1 is enlarged and bored out to receive a bushing or shell S, which is provided with the ports a, b, c, d and e; said shell being inserted within the casing to form a press fit therewith. The head A is provided with a conduit 5 which communicates with the upper tubes of the heater and also with a conduit or passage 4 which leads the feed water to the lower tubes. The shell S when pressed into the casing has its ports arranged in alignment with the various conduits as follows; port a with conduit 3, port b with conduit 4, port c with conduit 5, port d with conduit 6 and port e with conduit 7.

The valve plug 2 is divided by a web 2^a into a pair of passages 2^b and 8 which are adapted to furnish communication between the various ports and conduits in the following manner. When the plug 2 is set in the position shown in full lines in Fig. 2, it will be seen that the feed water passing through the heater will pass from the inlet conduit 3 through port a passage 2^b and port b to the conduit 4 and thence to the lower water tubes. After the water circulates through the heater it passes through conduit 5, port c, valve passage 8, and port d to the passage 6. When it is desired to cut the supply of feed water off from the heater, the valve plug 2 is turned to the position shown in dotted lines in Fig. 2, in which position the web 2^a cuts off the passage of the water to the ports c, b and e, and the passage 8 permits the water to flow from the conduit 3 directly to the conduit 6.

The draining position of the plug 2 is shown in Fig. 3, in which position it will be noted the passage 2^b establishes communication between both of the ports c and b leading to the top and bottom conduits 5 and 4 respectively, with the port e leading to the drain pipe 7, while the passage 8 establishes communication between the ports d, a, and e.

The cock described has the following advantages:

The combination of the body of the cock with the cover of the heater in one piece ensures that these parts are always at about the same temperature whether the feed is proceeding through the feedwater heater or directly.

Secondly, the cock in the position shown

in Fig. 3 allows the water to run out of the heater and at the same time admits air by way of the duct 5 to the top part of the feed water tubes. All the drainage paths 5 are of ample cross section so that the aerating of all the spaces is fully effected, both water connections are drained together the draining and aerating being effected by means of one cock with one manipulation.

10 What I claim as my invention and desire to secure by Letters Patent of the United States is:—

1. In a feed water heater a unitary structure comprising a head and a valve casing, 15 said head being provided with an inlet passage communicating with the lower portion of the heater and an outlet passage communicating with the upper portion of the heater, said valve casing being provided with a plurality of passages, for the inlet, the outlet, and the draining of the feed water to and 20 from said heater, a valve plug rotatably mounted in said valve casing and having a pair of passages which in one position of 25 said valve plug permit the passage of the feed water through said inlet and outlet passages to and from said heater respectively and which in another position establish communication between said draining passage 30 and all of the remaining passages of said head and valve casing.

2. In a feed water heater a unitary structure comprising a head and a valve casing, 35 said head being provided with an inlet passage communicating with the lower portion of the heater and an outlet passage communicating with the upper portion of the heater, said valve casing being provided with a plurality of passages, for the inlet, the out- 40

let, and the draining of the feed water to and 40 from said heater, a shell secured within said casing and provided with a plurality of ports respectively aligned with said passages, a valve plug rotatably mounted in said shell and having a pair of passages which in one 45 position of said valve plug communicate with predetermined ports of said shell to permit the passage of the feed water through said inlet and outlet passages to and from said heater and which in another position 50 communicate with all of the other ports of said shell to establish communication between said draining passage and all of the remaining passages of said head and valve casing. 55

3. In a header unit for a feed water heater, a member adapted to be secured to a wall of said heater, means forming passages in said member in communication with the upper and lower portions of said heater, respectively, a valve housing formed in said member and in communication with said passages, inlet, outlet and drain passages in said member communicating with said valve housing, a valve controlling said passages and adapted, in one position, to establish communication between the inlet and the lower portion of the heater and between the outlet and the upper portion of the heater; in a second position, to establish direct communication from the inlet to the outlet and between the heater passages and the drain passage; and in the third position, to establish communication between the drain passage and the other passages. 60 65 70 75

In witness whereof I have signed this specification.

OTTO GÜNTHER.
